UNITED STATES PATENT OFFICE.

MERRILL F. STUBBS, OF DENVER, COLORADO.

INTERNAL-COMBUSTION ENGINE.

Application filed August 17, 1926. Serial No. 129,788.

My invention relates to internal combustion engines and more particularly to explosion engines of the two cycle type.

It is an object of the invention to provide in an engine of the above stated character, a rotary element which by a uniform motion controls the intake, ignition and exhaust of gases, in connection with one or more cylinders of the reciprocating piston type. Another object of the invention is to provide in an internal combustion engine, a rotary element as stated above, in which is included a combustion chamber in connection with a source of fuel under pressure, and an ignition device in operative relation with a suitable timer.

A further object is to provide by means of a rotary control-element, a means for the rapid and complete discharge of inert gases in each cycle of the engine, so as to practically eliminate back pressure, and still other objects reside in details of construction and novel and useful arrangements and combinations of parts as will be fully disclosed in the course of the following description made with reference to the accompanying drawings:

In the drawings, in the several views of which like-parts are correspondingly designated,

Figure 1, represents a sectional elevation of a multiple-cylinder internal combustion engine constructed in accordance with my invention,

Figure 2, a section taken through one of the cylinders of the engine in the plane indicated by the line 2-2 in Figure 1, showing the respective part of the rotary element of the engine in its position at the point of ignition of the charge,

Figure 3, a similar view showing the positions of the rotary element and the piston halfway of its power stroke.

Figure 4, a similar view with the parts in the position in which the inert gases of combustion are beginning to exhaust,

Figure 5, a similar section showing the parts in position during full exhaust and fuel intake; and

Figure 6, an enlarged, fragmentary, sectional view of a portion of the housing of the rotary element, showing the construction of the packing strips employed to prevent leakage of motive fluid.

The engine illustrated in the drawings has four cylinders 5, the pistons 6 of which are

operated by the rotary movement of a single-control element divided into a corresponding number of sections by transverse partitions:

It is to be understood, however, that my invention is not limited to any particular number of cylinders and that it may be effectively employed in connection with a single-cylinder engine or with multiple-cylinder engines of any number of power-units.

The cylinders 5 may be cast en bloc as shown in Figure 1, in integral connection with an internally cylindrical housing 7 for the control-element 8 hereinafter to be described in detail. The housing is divided by transverse partitions 9 into four sections corresponding in position with the four cylinders, and it includes a concentric axially coincident tubular core 10 which may be made separate from the casting.

The core and the outer wall of the housing provide an annular space in which the control element is fitted for rotation. The housing has in its outer wall, openings 12, one for each of its sections, which communicate with the atmosphere for the exhaust of inert gases, and ports 25 which connect the interior of its sections with the respective cylinders.

The pistons 6 of the cylinders 5 are by means of rods 13 connected with a crank-shaft 14, the cranks 15 of which are, as usual, advanced at right angles to each other, and the control element 8 is connected with the crank shaft to rotate in unison therewith at a reduced velocity, as for example, a one to three ratio, by means of beveled gear wheels 16, 17, 18 and 19 two of which are at opposite ends of a jack-shaft 20, the ratio depending on the number of combustion chambers of the control element, for each cylinder of the engine.

The rotary element hereinbefore repeatedly referred to, comprises a cylindrical hollow body transversely divided into sections corresponding with those of the housing. The four sections of the rotary body fit snugly in the annular spaces of the housing-sections and are connected for conjunctive rotation by intermediate tubular parts 21 which extend through the transverse partitions of the housing, around the central tubular core of the same.

Each section of the rotary element is divided by webs 22 projecting radially inwardly from its peripheral wall, into three chambers 23 of equal size and form, which

have ports 24 in the periphery of the element, adapted to register with the fuel-port and the exhaust port of the corresponding section of the housing,

5 The rotary body has at one end a gudgeon 26 for its operative connection with the jack shaft by means of the beveled gear wheels 19 and 18.

10 The hollow core 10 of the housing 7 extends beyond the end thereof for its connection with a source of gaseous fuel under pressure, it has for each section of the housing a port 30 to admit the motive fluid to the chambers of the rotary element and it is further 15 provided with an internal duct 27 of smaller diameter, the end of which is connected with a blower or other similar appliance for the supply of air under pressure. The duct has in the periphery of the 20 core, ports 28 which communicate with the annular space of the housing in each section thereof, opposite to the exhaust openings 12 of the same for the purpose of scavenging the respective cylinders of the engine during 25 each cycle in the movement of the pistons.

The core of the housing has furthermore, opposite to the fuel-ports 25 communicating with the cylinders, openings 29 for the application of spark-plugs 36 the firing points 30 of which are in the openings. The spark plugs are connected with a suitable timing-device by wires, not shown in the drawing, which extend through the hollow core of the housing.

35 In the operation of the engine the four pistons are moved to impel the shaft by successive impulses upon its angularly disposed cranks, as is usual in engines of this type and it will be apparent that in order to obtain 40 the successive impulses of the ignited fuel charges upon the pistons, it is necessary that the chambers of the sections of the control element be relatively arranged to effect the supply and ignition of the fuel charges and 45 the exhaust of gases of combustion at the proper times in the movement of the respective pistons.

Inasmuch as the operation of each unit of the engine is identical to that of the other 50 units, as far as the successive steps thereof are concerned, a detailed explanation of the operation of any one of the units will suffice to convey a clear understanding of the operation of the entire invention and the advantages derived thereby.

To aid in the description, the three chambers produced by the radial webs of the rotary element have been designated in the drawings by the letters A, B and C, and the 60 direction of rotation has been indicated by the arrows D. When the piston is at the end of its inward stroke, as shown in Figure 2, the rotary control element is in the position in which the port 24 of its chamber 65 A is about to open into the port 25 between

the housing and the cylinder. At this point, the charge of fuel in the chamber A is ignited by the spark plug 36 and the force of explosion effects the power stroke of the piston, which is communicated to the crank-shaft by means of the piston rod 13. 70

In the position of the rotary element illustrated in Figure 2, the port 25 of the cylinder is closed, to be opened for the admission of the gases of explosion immediately upon ignition of the charge in the chamber A, and a fresh charge of fuel under pressure is admitted to the chamber C through the port 30 of the core 10 of the housing. 75

This condition is continued during further rotation of the element as shown in Figure 2, until the port 24 of the chamber A begins to open in the exhaust port 12 of the housing as indicated in Figure 4, when the spent gases are permitted to escape from the cylinder into the atmosphere. 80

The chamber C remains constantly in communication with the source of fuel supply until the rotor reaches the position shown in Figure 4, when the next following chamber B is connected with the source and the chamber A is brought in connection with the port 28 of the duct 27, to completely scavenge the cylinder by fluid pressure of the blower with which the duct is connected. 85 90

During the continued movement of the rotary element, the chamber C filled with compressed fuel gases, is brought to the position of the chamber A shown in Figure 2, fresh fuel is admitted to the chamber B by its connection with the port 30, and the spark plug is again operated by the timer to ignite the charge in the chamber C. 95 100

It will thus be seen that in each revolution of the rotor three explosions take place 105 in each of its sections while the cylinders are completely scavenged of inert gases in the intermediate periods.

In order to prevent the leakage of gases between the chambers of the rotor, packing strips are applied as indicated at 31 and illustrated in detail in Figure 6, and other packings may be used at different points if required. 110

It will be understood that the number of 115 chambers in the rotary control-element may be decreased or increased without departing from the principles of the invention, that the exhaust openings may be connected in a common manifold, and that other variations in the construction and arrangement of the parts comprised in the engine may be resorted to within the scope of the invention as defined in the hereunto appended 120 claims. 125

Simplicity of construction combined with great efficiency and practicability in use are salient features in the invention, and particular attention is directed to the fact that the admission of fuel to the cylinders and 130

the exhaust of gases never take place at the same time; excepting a negligible overlap, that the explosions of the charges in the chambers of the rotor take place when the 5 pistons approach the end of their inward strokes and that the valve-surface for both the intake and the exhaust of gases is large in comparison with those of other engines of similar type:

10 As stated hereinbefore the pistons move to the extreme ends of their cylinders, and the chambers of the rotary element are the combustion-chambers in which the fuel is ignited before being admitted to the cylinders through the ports 25.

It will be understood without further illustration that both the cylinders and the housing of the rotary control element may be provided with suitable cooling devices in 15 the usual manner.

Having thus described my invention, what I claim and desire to secure by Letters Patent is:—

1. In an internal combustion engine, a piston-cylinder; an annular housing having in its outer wall a port connecting with the cylinder, and an exhaust port, and having in its inner wall, a port for connection with a source of fuel-supply, a rotary control-element in the housing, divided into combustion-chambers each having ports adapted to register with the ports in the walls of the housing, and means to ignite the fuel-charge in each of the chambers at a determinate point in the rotary movement of the element.

2. In an internal combustion engine, a piston-cylinder, an annular housing having in its outer wall a port connecting with the cylinder, and an exhaust port, and having in its inner wall, a port for connection with a source of fuel-supply, a rotary control-element in the housing, divided into combustion-chambers each having ports adapted to register with the ports in the walls of the housing, and an ignition-device in an opening of the inner wall of the housing.

3. In an internal combustion engine, a piston-cylinder, an annular housing having in its outer wall a port connecting with the cylinder, and an exhaust port, and having in its inner wall, a port for connection with a source of fuel-supply, a rotary control-element in the housing, divided into combustion-chambers each having ports adapted to register with the ports in the walls of the housing, means to ignite the fuel-charge in each of the chambers at a determinate point in the rotary movement of the element, and a duct for connection with a source of pressure fluid, having a port in a wall of the housing, to scavenge the cylinder through the exhaust-port.

4. In an internal combustion engine, a piston-cylinder, an annular housing com-

posed of an outer wall having a port connecting with the cylinder, and an exhaust port, and a ported inner wall provided by a hollow core adapted for connection with a source of fuel-supply, a rotary control-element in the housing, divided into combustion-chambers each having ports adapted to register with the ports in the walls of the housing; and means to ignite the fuel charge in each of the chambers at a determinate point in the movement of the element.

5. In an internal combustion engine, a piston-cylinder, an annular housing having in its outer wall, a port connecting with the cylinder, and an exhaust port, and having in its inner wall, a port for connection with a source of fuel-supply, a rotary control-element in the housing, divided into combustion-chambers each having ports adapted to register with the ports in the walls of the housing, and an ignition device in the housing adapted to connect with the chambers, successively by the rotary movement of the element.

6. In an internal combustion engine, a piston-cylinder, an annular housing composed of an outer wall having a port connecting with the cylinder, and an exhaust port, and a ported inner wall provided by a hollow core adapted for connection with a source of fuel-supply, a rotary control-element in the housing, divided into combustion-chambers each having ports adapted to register with the ports in the walls of the housing, a duct in the hollow core, for connection with a source of pressure-fluid, having a port in the wall of the core to scavenge the cylinder through the exhaust-port, and means to ignite the fuel charge in each of the chambers at a determinate point in the movement of the element.

7. In an internal combustion engine, a piston-cylinder, a housing having a port connecting with the cylinder, and an exhaust port, a ported conduit for the supply of fuel to the housing, a rotary control-element in the housing, having combustion-chambers ported to connect successively with the conduit, the cylinder and the exhaust port, and means to ignite the fuel charge in each of the chambers at a determinate point in the movement of the element.

8. In an internal combustion engine, a piston-cylinder, a housing having a port connecting with the cylinder, and an exhaust port, a ported conduit for the supply of fuel to the housing, a rotary control-element in the housing, having combustion-chambers ported to connect successively with the conduit, the cylinder and the exhaust port, and an ignition device disposed to connect with the chambers, successively, by the rotary movement of the element.

9. In an internal combustion engine, a

plurality of piston-cylinders, a housing divided into annular compartments in axial alinement, each compartment having in its outer wall, a port connecting with one of the cylinders, and an exhaust port, and having in its inner wall a port for connection with a source of fuel-supply, a rotary control-element having sections in the compartments, each section being divided into combustion chambers and each chamber having ports adapted to register with the ports in the walls of the respective compartment, and means to ignite the fuel-charge in each of the chambers of each section at determinate points in the movement of the rotary element.

10. In an internal combustion engine, a plurality of piston-cylinders, a housing composed of an outer wall, a ported inner wall provided by a hollow core, and partitions dividing the space between the walls into axially alined annular compartments, each compartment having in its outer wall, a port connecting with one of the cylinders, and an exhaust port, a source of fuel supply connecting with the core, a rotary control-element having sections in the compartments, each section being divided into combustion-chambers and each chamber having ports adapted to register

with the ports in the walls of the respective compartment, and means to ignite the fuel-charge in each of the chambers of each section at determinate points in the movement of the rotary element.

35

11. In an internal combustion engine, a plurality of piston-cylinders, a housing composed of an outer wall, a ported inner wall provided by a hollow core, and partitions dividing the space between the walls into axially alined annular compartments, each compartment having in its outer wall, a port connecting with one of the cylinders, and an exhaust port, a source of fuel supply connecting with the core, a rotary control-element having sections in the compartments, each section being divided into combustion-chambers and each chamber having ports adapted to register with the ports in the walls of the respective compartment, a 40 duct having in the wall of the core, ports connecting with the compartments, a source of pressure-fluid connected with the duct, and means to ignite the fuel-charge in each of the chambers of each section at determinate points in the movement of the rotary element.
